UNITED STATES PATENT OFFICE.

JAMES L. COX, OF BERGHOLZ, OHIO.

REPEATING SHOTGUN.

1,111,440.

Specification of Letters Patent. Patented Sept. 22, 1914.

Application filed June 19, 1914. Serial No. 846,130.

To all whom it may concern:

Be it known that I, JAMES L. Cox, a citizen of the United States, residing at Berg-
holz, in the county of Jefferson and State
of Ohio, have invented certain new and use-
ful Improvements in Repeating Shotguns;
and I do hereby declare the following to be
a full, clear, and exact description of the
invention, such as will enable others skilled
in the art to which it appertains to make
and use the same, reference being had to the
accompanying drawings, and to the letters
and figures of reference marked thereon,
which form a part of this specification.

This invention relates to new and useful
improvements in repeating shot guns and
the object in view is to produce a simple
and efficient device of this nature in which
the parts of the gun are reduced to a mini-
mum.

More specifically, the present invention
consists in the provision of a repeating shot
gun in which the breech mechanism is en-
tirely inclosed within the casing at all times.

The invention comprises further various
details of construction, combinations and ar-
rangements of parts which will be herein-
after fully described, shown in the accom-
panying drawings and then specifically de-
fined in the appended claims.

My invention is illustrated in the accom-
panying drawings, in which:

Figure 1 is a side elevation of a portion
of the gun made in accordance with my in-
vention. Fig. 2 is an enlarged view in ele-
vation with the one side of the casing re-
moved, showing the breech block in its
locked position. Fig. 3 is a view in eleva-
tion showing the breech block at its farthest
rearward throw, the parts being in pos-
ition to receive a shell. Fig. 4 is a view in
elevation showing the breech block fed for-
ward a slight distance in the act of pushing
the shell into the barrel of the gun. Fig.
5 is a cross sectional view on line 5—5 of
Fig. 4, and Fig. 6 is a detail edge view of a
shell extracting finger.

Reference now being had to the details
of the drawings by numeral, 1 designates
the casing of the gun containing the opera-
tive parts of the breech mechanism, 2 the
barrel and 3 the forward stock section which
incloses the magazine 4. Mounted within
the chambered portion of the casing is the
breech block 5, which, in Fig. 2, is shown
at its farthest forward throw and in a locked

position and in Fig. 3 the breech block is
illustrated as being positioned at its rear-
most position to allow a shell to be delivered
from the magazine in front of the breech 60
block and driven forward into the chamber
of the barrel.

Mounted to have a reciprocating move-
ment over the lower portion of the forward
part of the stock is the sliding handle 6 of 65
the usual construction employed in repeat-
ing shot guns, and 7 designates an action
bar which is mounted to have a reciprocat-
ing movement within a recess 8 formed in
the inner face of the casing, as shown clearly 70
in Fig. 5 of the drawings. Said action bar
is connected through the medium of a screw
9 passing through registering apertures in
the walls of the handle and engages a hole
in the sliding bar. Said pin also passes 75
through elongated registering slots 10
formed in the forward stock 3 and serving
to guide the handle in the operation of the
gun. The rear end of the action bar is
provided with an aperture engaged by the 80
pin 11, shown clearly in Figs. 3 and 4 of
the drawings, and which pin is carried by
the breech locking member 12 which is
forked, forming two arms 13, pivotally
mounted upon a pin 14 which passes through 85
the breech block. It will be noted upon re-
ference to the drawings that the breech block
is provided with two recesses 15, on oppo-
site sides thereof and in which the two arms 90
13 of the breech locking member are posi-
tioned. The rear end of said locking mem-
ber has a hook-shaped projection 16 which
serves as a means for protecting the firing 95
pin 17 when the breech block is driven rear-
ward to receive a shell to be fed forward
into the barrel of the gun. Said firing pin
is mounted in a slightly diagonally disposed
aperture extending through the breech block.
One face of the breech block is recessed
away as at 18 to receive a resilient shell ex- 100
tracting finger 19, the forward end of which
has a diagonally hook-shaped projection for
engagement with the rim of a shell. Said
locking member 12 has a cam-shaped pro-
jection 20 upon the free end thereof, said 105
cam-shaped projection terminating at one
end in an inclined shoulder 21, the pur-
pose of which will presently appear.

Pivotaly mounted upon a pin 22 is a
tilting shell lifting member 23 which has 110
an elongated slot 24 near its forward free
end and through which slot a lifting finger

25 passes and which is mounted upon a pin 26, shown clearly in Figs. 3 and 4 of the drawings, the purpose of which finger is to elevate the rear end of the shell while the latter is being raised to position to be driven forward by the breech block into the breech and thereby avoid any jamming of the shell which is a common trouble with repeating shot guns commonly in use.

10 Positioned in a recess immediately at the forward end of the shell lifting member is a resilient cartridge stop 27, the rear end of which is fastened to a pin 28 and the forward end is adapted to engage the rim 29 of a shell 30 within the magazine in readiness to cause the shell to be released from the magazine when it is desired to deliver the same into the barrel of the gun. Pivotaly mounted upon a pin 31 carried by the 15 rear end of the shell lifting member is a pawl 32, and 33 is a coiled spring which bears intermediate the bottom of a recess 34 formed in the side of the shell lifting block and said pawl, the purpose of which 20 is to normally hold the pawl at its farthest inner throw so that the upper edge thereof will be disposed in the path of the inclined shoulder 21 when the breech block is thrown back from its forward position to that illustrated in Fig. 3, allowing the pawl to swing 25 out idly without causing the shell lifting member to be tilted. It will be noted that said pawl has its upper rear edge inclined as at 35 and against which the inclined edge 36 of the cam-shaped projection 20 is adapted to contact as the breech block is moved forward from its rearmost position, thus causing the forward end of the shell raising member to be thrown up to the position 40 shown in Fig. 4 of the drawings for the purpose of raising a shell previously withdrawn from the magazine to a position to be driven into the barrel on the forward movement of the breech block.

45 During the tilting of the shell raising member, the finger 25, before referred to, is thrown to an inclined position as illustrated and, coming in contact with the rear portion of the shell, will tend to lift the same up to 50 a position in alinement with the barrel so as to avoid any possibility of the cartridge jamming when driven forward by the breech block. The breech block is driven forward and the projecting portion 37 thereof comes 55 in contact with the shoulder 40 and a further forward movement of the sliding handle will cause the action bar to move therewith and, as the rear end of said bar is pivotally connected with the locking block 60 12, the latter will be caused to swing from the position shown in Fig. 3 to the position shown in Fig. 2 with the convexed or cam edge 41 of said locking block in contact with the upper edge of the lug 42, which is 65 formed integral with the lower wall of the

casing. This swinging movement of the locking block will throw the rear end of the breech block to the position shown in Fig. 2 in which its upper end will bear against the shoulder 44, thus forming an abutment 70 means for the breech block.

The hammer is designated by numeral 45 and is pivotally mounted upon a pin 46, the lower part 47 of the hammer projecting through a slot in the bottom of the casing. 75 The trigger 48 is pivotally mounted upon a pin 49 and its body portion is slotted as at 54. A hammer spring 51 is fastened at one end to the bottom of the casing and extends through said slot and engages a hole 80 52 formed in the edge of the hammer. Said hammer, it will be noted, is provided with a hook 53, on the rear edge thereof, which automatically engages over the crosspiece 50 at the upper end of the trigger in the 85 manner shown in Fig. 3 of the drawings and serves to hold the hammer in a cocked relation.

It will be noted upon reference to the drawings that the upper edge of the shell 90 lifting member 23 is slightly inclined as at 55 and is designed to engage and depress the shell holding member 27 when the breech block is at its forward limit for the purpose of allowing a shell to be driven by the 95 spring plunger 56 within the magazine to a position to be raised by said shell lifting member. This action of the tilting shell lifting member to release a shell in the magazine by the depression of the member 100 27 is substantially simultaneous with the locking of the breech block in the position shown in Fig. 2 of the drawings.

A shoulder 63 formed upon the inner wall of the casing is so positioned that, when a 105 shell is withdrawn from the barrel, the rim of the shell will come against the same and arrest further rearward movement of the shell, simultaneous with the throwing of the same laterally by the hooked end of the 110 shell extractor 19 which will yield when the rim comes against the shoulder, thus quickly throwing the shell out through the opening in the casing. The side of the casing is provided with an opening 60 through which 115 opening the shells are placed within the casing as they are fed into the magazine and through which opening the shells are thrown out after being fired. A closure 62 to said opening is fastened to the breech block and 120 moves therewith and automatically opens as the breech block is thrown rearward and closes as the block is moved forward in the act of delivering the shell into the barrel.

The operation of my gun will be readily 125 understood and is as follows:—The shells being first inserted in the magazine, when it is desired to throw a shell into the barrel of the gun, the operator pulls back upon the sliding handle, the first act being to throw 130

the rear end of the breech block down so that the upper portion of the rear end thereof will clear the abutment shoulder 44, this being accomplished by the swinging movement 5 of the locking member which is pivotally connected to the action bar. As the breech block moves backward, the shell extractor, the forward end of which engages over the rim of the shell, will cause the shell 10 to be withdrawn from the barrel and, when the rim of the shell comes in contact with the shoulder 63 and its further backward movement is arrested thereby, the shell extractor will yield slightly and throw the shell 15 laterally out through the opening 60 in the casing, the closure being drawn back with the breech block to allow the shell to be thrown out. As the beveled shoulder 21 upon the cam-shaped edge of the locking member 20 comes in contact with the inclined edge of pawl 32, the latter will be thrown laterally upon its pivot to allow the locking block to pass to its farthest rearward position without operating the tilting shell lifting member. By moving the sliding handle 25 forward, the inclined edge 36 upon the cam projection 20, coming in contact with the inclined edge 35 of the pawl, will cause the latter to tilt down the rear end of the shell 30 raising member, thus lifting the shell and also the tilting finger which raises the rear end of the shell, as shown in Fig. 4 of the drawings, preparatory to the shell being driven forward by the breech block into the barrel without any danger of jamming. After the cam-shaped projection of said locking member passes by the pawl, the shell is driven forward into the barrel and the lifting member quickly returns to its normal 35 position. As the forward end of the breech block comes in contact with the shoulder 40, the shell will have been driven to its proper position within the barrel and a further forward sliding movement of the handle 40 will cause the locking block to tilt upon its pivot to the position shown in Fig. 2 of the drawings, in which its lower convexed edge, coming in contact with the upper end of the lug 42, will cause the rear end of the breech block 45 to be thrown into a positively locked position against the abutment shoulder 44, after which the gun may be fired by pulling upon the trigger to release the hammer which is thrown by the hammer spring 50 against the rear end of the firing pin. It will be noted that, unless the breech block is in a securely locked position, it will be impossible for the hammer to strike the firing pin by reason of the hook-shaped projecting end 55 of the locking member forming an abutment surface against which the hammer would contact, thus producing a safety device which will positively insure the shell being locked within the barrel before it will 60 be possible to fire it.

Should it be desired to disconnect the hammer from the trigger as a safety means when the shell is within the barrel, it may be done by the operator holding the lower projecting end of the hammer against the tension of the spring bearing against the same after the hooked end of the hammer is released from the slot in the end of the trigger and, in the event of it being desired to cock the gun, it may be automatically done by 70 simply throwing forward the lower projecting end of the hammer until the hooked end thereof snaps over the slotted end of the trigger.

What I claim to be new is:—

1. A repeating shot gun having a pivotally mounted shell raising member, means actuated by the latter for causing the shell to aline with the barrel as the shell is raised, a sliding action bar, a breech block actuated thereby, a spring-pressed pawl pivotally mounted upon said pivotal member, and means upon the breech block designed to contact with said pawl to cause the member to tilt as the breech block moves in one direction. 80

2. A repeating shot gun having a pivotally mounted shell raising member, means actuated by the latter for causing the shell to aline with the barrel as the shell is raised, a sliding action bar, a breech block actuated thereby, a spring-pressed pawl pivotally mounted upon said pivotal member, a locking member pivotally mounted upon the breech block and having a projecting portion thereof adapted to contact with said pawl to cause said pivotal member to tilt as the breech block moves in one direction. 95

3. A repeating shot gun having a pivotally mounted shell raising member, means actuated by the latter for causing the shell to aline with the barrel as the shell is raised, a sliding action bar, a breech block actuated thereby, a spring-pressed pawl pivotally mounted upon said pivotal member, a locking member pivotally mounted upon the breech block and provided with a cam projection having a beveled portion, which projection is designed, as the breech block is moved forward, to contact with said pawl to cause the shell raising member to tilt, the pawl moving idly on the return movement of the breech block. 100

4. A repeating shot gun having a pivotally mounted shell raising member, means actuated by the latter for causing the shell to aline with the barrel as the shell is raised, a breech block and a firing pin carried thereby, a locking member pivotally mounted upon the breech block, a sliding action bar pivotally connected to said locking member, an abutment against which the locking member is adapted to contact to elevate the breech block to a locked position, a spring-pressed pawl upon the shell lifting member, 110 115 120 125 130

1 said locking member having a projection adapted to contact with the pawl to cause the shell lifting member to tilt as the breech block moves forward, a spring-pressed hammer and a trigger for engagement with the same.

5. A repeating shot gun having a pivotally mounted shell raising member, means actuated by the latter for causing the shell 10 to aline with the barrel as the shell is raised, a breech block and a firing pin carried thereby, a locking member having a cam edge and a hook portion, a spring actuated pawl pivotally mounted upon the shell raising member 15 and disposed in the path of said projection, a stationary abutment against which the cam edge of said locking member is adapted to contact to throw the rear end of the breech block into a locked position, a 20 spring-pressed hammer and a trigger for engagement with the same.

6. A repeating shot gun having a pivotally mounted shell raising member, means actuated by the latter for causing the shell 25 to aline with the barrel as the shell is raised, a breech block and a firing pin carried thereby, a locking member having a cam edge and a hook portion, said shell raising member having a recess in the face thereof, a spring- 30 pressed pawl mounted within said recess and having its upper edge angular and positioned in the path of the projection upon the locking member, affording means whereby, as the breech block is moved forward, a 35 projection upon the locking member will cause the shell raising member to tilt, the pawl operating idly on the return movement of the breech block, a spring-pressed hammer and a trigger.

40 7. A repeating shot gun comprising a casting having a shoulder formed in the inner surface of the upper portion thereof, a sliding breech block, a pivotal locking member carried by the breech block, an action bar 45 pivoted to said locking member, the latter being provided with a hooked portion and a cam edge, a pivotal shell raising member, means actuated by the shell raising member for causing the shell, when raised, 50 to aline with the barrel, a pawl carried by the shell raising member and positioned in the path of the projection of said locking

member, an abutment forming a part of the casing and against which the cam edge of the locking member is adapted to contact to 55 cause the rear end of the breech block to be raised against said shoulder in the casing, a firing pin carried by the breech block, a spring-pressed hammer and a trigger.

8. A repeating shot gun comprising a cas- 60 ing having a shoulder formed in the inner surface of the upper portion thereof, a sliding breech block, a pivotal locking member carried by the breech block, an action bar pivoted to said locking member, the latter 65 being provided with a hooked portion and a cam edge, a pivotal shell raising member, means actuated by the shell raising member for causing the shell, when raised, to aline with the barrel, a pawl carried by the 70 shell raising member and positioned in the path of a projection of said locking member, an abutment forming a part of the casing and against which the cam edge of the locking member is adapted to contact to 75 cause the rear end of the breech block to be raised against said shoulder in the casing, a firing pin carried by the breech block, a 80 hammer pivoted within the casing having a hooked portion, a trigger pivoted to the casing and having an opening therein over the edge of which the hooked end of the hammer engages, and a spring fastened to the casing, passing through said opening and en- 85 gaging the hammer.

9. A repeating shot gun comprising a cas- 90 ing, a pivotal shell raising member mounted therein and having an opening therein, a finger pivoted to the casing and movable through said opening and adapted, as the member is tilted, to cause a shell, when raised upon the latter, to aline with the barrel, a breech block, an action bar for moving said block, a pawl upon the shell raising member, means carried by the breech block 95 and adapted to actuate said pawl for tilting the member, a firing pin in the breech block, and a hammer and trigger.

In testimony whereof I hereunto affix my signature in presence of two witnesses.
